UNITED STATES PATENT OFFICE.

WILLIAM G. KENDALL, OF NEWARK, NEW JERSEY.

VANITY-CASE HINGE.

Application filed July 3, 1926. Serial No. 120,332.

This invention relates to vanity cases and particularly to an improved hinge therefor and has for an object to provide an improved structure wherein the exterior part of the case is left smooth and even.

Another object of the invention is to provide a hinge in which practically all of the parts are arranged interiorly of the casing.

A further object, more specifically, is to provide a hinge formed in two parts and pressed from the top and body of the case.

In the accompanying drawing—

Figure 1 is a perspective view of a vanity case provided with a hinge embodying the invention.

Figure 2 is a sectional view through Figure 1 on line 2—2, the same being on an enlarged scale.

Figure 3 is a fragmentary perspective view of part of the vanity case with a pintle structure ready for receiving the hinge knuckle.

Figure 4 is a view of the structure shown in Figure 3 before the pintle has been formed into its completed shape.

Figure 5 is a detail fragmentary sectional view similar to the left hand portion of Figure 2 but shown on a greatly enlarged scale but illustrating more accurately the position of the various parts.

Figure 6 is a fragmentary top plan view of part of the case shown in Figure 1, illustrating in a rather exaggerated way the flat condition of the hinge and associated parts.

Referring to the accompanying drawing by numerals, 1 indicates the body of the case, said body having an annular upstanding flange 2, which flange is provided with an offset portion 3 for receiving the lower part of the depending flange 4 of the cover or lid 5. The flange 2 is provided with four cuts 6 which permit the sections 7 and 8 to be bent into substantially arc-shaped formations whereby the completed pintle 9 is produced. The integral sections 10 and 11 are preferably pressed so as to offset the pintle 9 inwardly as shown in Figure 5, said offsetting being of approximately the thickness of flange 2. By reason of this construction, the knuckle 12 formed from an extension of flange 4 may be looped or bent inwardly for encircling the pintle 9 and the exposed portion of the hinge caused to be flush with the exterior surface of flange 2.

What I claim is:

A vanity case, comprising a flanged body, the flange of the body having a cut out portion and provided with an integral tubular pintle, said pintle being of a length equal to the cut out portion, disposed therein intermediate the depth thereof and offset inwardly a distance equal to the thickness of said flange, and a flanged cap, the flange of the cap having at the edge an extension of a width equal to the said cut out portion and bent around said tubular pintle.

WILLIAM G. KENDALL.
